A. T. Merriman,
 Tile Machine,
 №60,922, Patented Jan. 1, 1867.

United States Patent Office.

ANDREWS T. MERRIMAN, OF RUTLAND, VERMONT.

Letters Patent No. 60,922, dated January 1, 1867.

IMPROVED MACHINE FOR SQUARING TILES.

The Schedule referred to in these Letters Patent and making part of the same.

TO ALL WHOM IT MAY CONCERN:

Be it known that I, ANDREWS T. MERRIMAN, of Rutland, in the county of Rutland, and State of Vermont, have invented a new and useful improvement in Machine for Squaring Tiles; and I do hereby declare that the following is a full, clear, and exact description thereof, which will enable others skilled in the art to make and use the same, reference being had to the accompanying drawings, forming part of this specification, in which—

Figure 1 represents a side elevation of this invention.

Figure 2 is a transverse vertical section of the same.

Similar letters of reference indicate like parts.

This invention relates to an improvement in the method of hanging the frame in which the tiles are clamped during the operation of grinding off their edges, and also to certain improvements in the construction of said frame, whereby the same can be readily adjusted for tile of different size.

The machine which I use for squaring or grinding off the edges of tiles is constructed of a frame, A, of wood or any other suitable material, the top and bottom cross-bars of which form the bearings for a vertical arbor, B, on which the grinding disk or plate C is mounted. This arbor receives a revolving motion from the driving-shaft D, which connects the same by a bevel gear, a b, or in any other suitable manner. The tiles to be ground or squared are fastened in a swinging frame, E, which is composed of a vertical plate, e, from which two arms, d, extend in a horizontal direction, and through the end of these arms passes a pin, e, which has its bearings in suitable brackets, f, attached to one of the uprights of the main frame A. The plate e is thus free to swing back and forth, and also to rise and fall freely until one of its arms strikes an adjustable collar, g, which is secured on the pin e in the desired position by means of a set-screw, h. The plate e is provided with a clamp, i, which is operated by a thumb-screw, j, (see fig. 2) and which serves to secure the tiles to be ground or squared on the plate e. Said clamp is composed of a hinged lever, through one end of which passes the thumb-screw j, whereas its opposite end is furnished with a soft or elastic pad, k, so that the same when pressed down upon a tile will not injure or break it. The tiles are adjusted in the desired position by means of a stationary lip, l, projecting from the plate e, and by a gauge, m, which is adjustable on said plate by set-screws, n. This gauge is adjusted to correspond to the size of the tile to be ground, and the tiles are secured to the plate e one after the other by means of the clamp i, and by allowing its edge to bear down on the grinding disk C the surplus is taken off. The distance to which the plate e with the tile is permitted to sink down is determined by the adjustable collar g, which is set to correspond to the size of tile under operation, and the operation of grinding or squaring tiles can be carried on with the greatest facility and without requiring much attention. By swinging the plate e back and forth on the pin e, the tile is prevented from bearing down upon the same spot on the grinding disk, and the surface of said disk is preserved even, and the operation of grinding is facilitated. The tiles are easily secured in position, and, if desired, the plate e and the gauge m can be readily adjusted for hexagonal or octagonal tiles, or for tiles of any other shape.

What I claim as new, and desire to secure by Letters Patent, is—

1. The vertical pin e, in combination with the plate e, to which the tiles are clamped, substantially as herein described; so that the plate can rise and fall and sweep over the grinding disk in a circular or oscillating motion.
2. The adjustable collar g, in combination with rising and falling swinging plate e, constructed and operating substantially as and for the purpose set forth.
3. The clamp i, composed of a hinged lever with thumb-screw and elastic pad, as and for the purpose described.
4. The adjustable gauge m, in combination with the clamp i and plate e, constructed and operating substantially as and for the purpose set forth.

Witnesses:

FAYETTE VAUGHN,
H. F. REYNOLDS.

ANDREWS T. MERRIMAN.
